[57] CLAIM

The ornamental design for a display drawer for compact discs or the like, as shown and described.

DESCRIPTION

FIG. 1 is a part and top-left perspective view of a display drawer for compact discs or the like showing my design;

FIG. 2 is a right side elevational view thereof;

FIG. 3 is another right side elevational view thereof, showing the cover in an open position;

FIG. 4 is a bottom plan view thereof; and

FIG. 5 is a rear elevational view thereof.

FIG. 1

FIG. 2

FIG. 3
